UNITED STATES PATENT OFFICE.

REGINALD A. FESSENDEN, OF WASHINGTON, DISTRICT OF COLUMBIA, ASSIGNOR, BY MESNE ASSIGNMENTS, TO SAMUEL M. KINTNER, OF PITTSBURGH, PENNSYLVANIA, AND HALSEY M. BARRETT, OF BLOOMFIELD, NEW JERSEY, RECEIVERS.

WIRELESS SIGNALING.

1,176,282.

Specification of Letters Patent. Patented Mar. 21, 1916.

Original application filed December 14, 1904, Serial No. 236,862. Divided and this application filed August 21, 1905. Serial No. 275,163.

To all whom it may concern:

Be it known that I, REGINALD A. FESSENDEN, a citizen of the United States, and resident of Washington, District of Columbia, 5 have invented certain new and useful Improvements in Wireless Signaling, of which the following is a specification.

The invention herein described relates to improvements in apparatus for wireless te- 10 legraphy and has special reference to the apparatus employed for producing indications.

The invention is hereinafter more fully described and claimed.

In the accompanying drawings forming a 15 part of this specification, Figures 1 and 2 are diagrammatic views illustrating different forms of this invention.

The current or voltages generally produced in the indicating circuit at the receiving station of the wireless telegraph system are sufficient to operate a telephone or other delicate indicating instrument, but are not sufficient to actuate a call or a recording mechanism directly. This is a great disad- 20 vantage in the art, as it does not permit of the receiving station being called up when it is desired to communicate with it.

In the practice of my invention two frequencies are generated at the sending station, one being the wave frequency and the other the frequency of the groups into 30 which the waves are divided, called a group frequency. Currents or voltages which have the same frequency as the group frequency 35 are thereby produced in the indicating circuit at the receiving station.

In order to obtain an increased effect to 40 permit the use of a call or a recording mechanism I employ in the receiving station a source of intermittent or alternating current having the same frequency as the group frequency of the signaling impulses. Other frequencies independent of the wave frequency may be used in lieu of the group frequency, but the group frequency is generally preferred. By the use of this independent 45 source of intermittent or alternating current, I obtain a powerful alternating magnetic field and arrange in said field a coil or 50 coils connected in the receiver circuit through which flow the currents produced by the receiver waves having a frequency the

same as the group frequency of the sending station, so that there will be a mutual action between this coil or coils and the independent 55 alternating magnetic fields.

As the independent alternating magnetic field may be made as strong as desired, the amount of this interaction may be made very much greater than would otherwise be 60 the case.

It is preferred that the frequency of the independent alternating current source should differ slightly from that of the group frequency at the sending station in order to 65 prevent the phases of the independent alternating magnetic field and the current in the receiver circuit from accidentally becoming such as to produce no interaction, in which case, of course, no indication would be produced but a dead point would exist. By 70 making the frequency slightly different this possibility of no response is obviated, as the phase difference is constantly changing.

In Fig. 1, 1 is a receiving antenna grounded at 2, 3 is the primary and 4 the secondary of the transformer, the detector 5 and condenser 6 being in the secondary circuit. The secondary circuit 4 and the receiving conductor are preferably tuned to the wave frequency. 7 is a potentiometer. 8 is a source of alternating current and 9 a means of regulating the current, 10 is an indicating mechanism, for example a siphon recorder or relay, 11 is the battery of the local circuit. 12 and 13 are coils in the local alternating circuit wound upon the magnet 14, which is constructed of laminated iron. 15 and 16 are coils in series with each other and arranged in the receiver circuit as shown and carrying contact points 17 and 18 adapted to close the local circuit 10, 11. The coils 15 and 16 are wound oppositely so that the voltages induced by the alternating flux of the magnet 14 neutralize each other. An 80 exact neutralization can be obtained by any suitable means, as for example, by a shunt 85 19 placed around one of the coils whereby to vary the resistance to any current flowing or by adjusting the angle at which one of 90 the coils naturally rests as by spring 6a. 95

With the construction here shown the receiver 5 being a liquid barretter, a continuous current will constantly flow through the

coils 15 and 16 but since the magnetic flux from the magnet 14 is alternating, the coils will not tend to move. Should, however, electromagnetic waves reach the receiving station intermittent currents caused thereby and having the same frequency as the group frequency at the sending station, will flow through the coils. These fluctuating currents will interact with the magnetic field 10 caused by the local source 8 and will cause one coil to move in one direction and the other coil in the other direction, since the coils are oppositely wound. Hence the contacts 17 and 18 will approach each other and 15 close the circuit of call or recording or other mechanism 10.

Fig. 2 shows another form, in which the receiver is a magnetic receiver and the coil 5 of the magnetic receiver in the circuit of 20 which the telephone is usually placed is connected to a movable coil 20 placed at right angles to a fixed coil 21. The local alternating current from the source 8 flows through the fixed coil, and the variable currents from the magnetic receiver flow through the movable coil 20. The movable coil carries a contact point 22 which when the coil is moved closes a local circuit containing an indicating mechanism 23 and 25 battery 24. The neutralization of the voltage in the coils 20 and 21 may be effected by allowing one coil to swing freely and making the other coil adjustable in the field as by spring 21^a. This spring must have 30 just exactly the right force to restore the coil to neutral position, after it has been 35 displaced by the received signal.

The method herein described is not here 40 claimed but is claimed in my co-pending application No. 236,862, filed Dec. 14th, 1904, of which this application is a division.

What I claim is:

1. In a system of signaling by electro-magnetic waves the combination at the receiving station of means for producing an alternating magnetic field, a magnetic receiver for electro-magnetic waves, a movable coil in operative relation to a circuit controlled by the receiver and arranged in 45 the magnetic field, and a signaling mechanism controlled by said coil.
2. In a system of signaling by electro-magnetic waves, the combination at the receiving station of local means for producing an alternating field, means for producing a 50 second intermittent field by impulses transmitted from the sending station, said fields being arranged to inter-act, means for producing an indication by the inter-action of 55 these fields and adjusting means for compensating the action of the local alternating field.
3. In a system of signaling by electro-

magnetic waves, the combination at the receiving station of local means for producing 65 an alternating field, means for producing a second intermittent field by impulses transmitted from the sending station, one of said fields being fixed and the other movable and said fields being arranged to inter-act, means for producing an indication by the inter-action of these fields and adjusting means for compensating the action of the local alternating field.

4. In a system of signaling by electro-magnetic waves, the combination at the receiving station of local means for producing an alternating field, means for producing a second intermittent field by impulses transmitted from the sending station, one 80 of said fields being fixed and the other movable and said fields arranged to inter-act, means for producing an indication by the inter-action of these fields and means for 85 annulling the local action of the local magnetic field.

5. In a system of signaling by electro-magnetic waves, the combination at the receiving station of local means for producing an alternating field, means for producing a 90 second intermittent field by impulses transmitted from the sending station, one of said fields being fixed and the other movable and said fields arranged to inter-act, means for producing an indication by the inter-action 95 of these fields and means for annulling the local action of the local magnetic field on the movable element.

6. Apparatus for detecting periodic electric impulses, comprising a coil and a generator arranged to produce an alternating field, a second coil arranged to be traversed by the impulses to be detected and thereby produce a second intermittent field, means to neutralize the action of the first named 100 field on the indicator, and an indicator operated by interaction of the two fields to produce an indication of the said impulses, substantially as described.

7. In apparatus for detecting periodic 110 electric impulses, the combination of a coil and means to maintain an alternating field thereby, a second coil and means to cause a current produced by impulses to be detected to flow therethrough, adjustable means to 115 neutralize the action of the first named field on the indicator, and an indicator operated by the interaction of the two fields, substantially as described.

Signed at Brant Rock, Plymouth Co., 120 Mass., this 18th day of August, A. D. 1905.
